UNITED STATES PATENT OFFICE.

EDWARD F. McKENNA, OF NEW RICHMOND, WISCONSIN.

FOLDING LEG.

SPECIFICATION forming part of Letters Patent No. 783,456, dated February 28, 1905.

Application filed February 9, 1904. Serial No. 192,738.

To all whom it may concern:

Be it known that I, EDWARD F. McKENNA, a citizen of the United States, residing at New Richmond, in the county of St. Croix and State 5 of Wisconsin, have invented new and useful Improvements in Folding Legs, of which the following is a specification.

My invention relates to folding legs for beds, cots, and the like, and has for its object to provide an improved construction of the same that will firmly retain the leg either in its open 10 or folded position and without the aid of additional fastening devices. This object I accomplish in the manner and by the means hereinafter described and claimed, reference being 15 had to the accompanying drawings, in which—

Figure 1 is a side elevation of a section of the side rail of a bed or cot having my improved device thereon, the leg being shown 20 in its open position. Fig. 2 is a similar view, the leg being shown in its folded position. Fig. 3 is a central vertical sectional view of the bracket for holding the leg in either position.

Similar numerals of reference denote corresponding parts in the several views.

Referring to said drawings, the reference numeral 1 denotes the side rail of a bed or cot to which is attached, by screws 2 or otherwise, 30 a bracket consisting of a back plate 3, an intermediate portion 4, and a front plate 5, said parts being formed, preferably, of metal and being formed either in one piece or in separate pieces permanently fastened together. The 35 intermediate portion 4 is formed centrally with an inverted-V-shaped slot or recess 6, and at one side is cut away almost horizontally to provide an angled face, as shown in dotted lines at 7 in Fig. 1, and on its other side is cut 40 away to provide an angled face more nearly approaching the vertical, as also shown in dotted lines at 8 in Fig. 1, all for a purpose hereinafter to be described.

The leg 9 may be of any desired shape, except that its upper end 10 shall be of a width to enter the space between plates 3 and 5, and shall be of inverted-V shape to correspond accurately with the slot 6. The upper end 10 of said leg is provided with an elongated slot

11, adapted to receive a pin 12, fixed in registering apertures 13 in the plates 3 and 5.

From the above description the operation of my improved construction will be understood to be as follows: The leg 9, attached to its bracket by means of pin 12 engaging the elongated slot 11 therein, is vertically movable in said bracket to the extent of the length of said slot; but when forced upward its inverted-V-shaped end 10 engages the similarly-shaped slot 6 in the bracket, thus firmly wedging said 60 leg in the vertical position for use, as seen in Fig. 1. To fold the leg it is only necessary to draw the same downward out of engagement with said slot 6 and to turn it on the pin 12 as a pivot to a horizontal position 65 against the angled face 7, and then force it endwise toward the angled face 8, whereupon it will wedge between said faces 7 and 8 and be firmly retained in the folded position parallel with the side rail 1, as shown in Fig. 2. 70

It will be understood that the angle of the face 7 will be arranged to suit the configuration of the leg 9, so as to permit the latter to assume a horizontal position, and may be varied to suit a leg of different shape from 75 that shown in the drawings.

While it is preferred to form the bracket receiving the leg separate from the side rail of the article of furniture to be supported, still I do not wish to limit myself to such construction, as the parts engaging the upper end of the leg may be formed integral with the side rail. So, also, although I have shown the leg 9 and its upper end 10 formed integral, the two may be formed separate and attached together by screws or other suitable means. So constructed the upper end 10 and the bracket would constitute an article of manufacture capable of sale as such. It may also be desired to provide additional means for 85 firmly retaining the leg in either adjusted position, which may be readily done by replacing the pin 12 with a thumb-nut, whereby the parts may be clamped together when adjusted and as readily released to shift the same. 90

Having thus described my invention, what I claim as new, and desire to secure by Letters Patent, is— 95

The combination with a leg having an angular upper end, of a bracket having a similarly-shaped slot or recess to receive the angular upper end of said leg and retain it in a vertical position, and having angled faces adapted to engage said leg when in a horizontal or folded position, said leg and bracket having a slotted connection permitting movement to the former from the one position to the other and co-

operating with said angled faces to wedge to said leg in its horizontal or folded position.

In testimony whereof I have hereunto set my hand in the presence of two subscribing witnesses.

EDWARD F. McKENNA.
